(57) **CLAIM**

The ornamental design for a bracelet attachment tool, as
shown and described.

DESCRIPTION

FIG. 1 is a top plan view showing my new design;

FIG. 2 is a bottom plan view;

FIG. 3 is a front elevational view;

FIG. 4 is a left side elevational view;

FIG. 5 is a right side elevational view; and,

FIG. 6 is a rear elevational view.

The broken line showing of the clip is for illustrative
purposes only and forms no part of the claimed design.
